(57) **ABSTRACT**

An audio processing apparatus includes a first microphone, a second microphone, and a masking unit configured to mask movement of air from outside of the apparatus to the second microphone. A filter coefficient is estimated and learned so as to minimize the difference between the output signal of the first microphone and the output signal of the second microphone, thereby suppressing a reverberation component generated in the closed space between the masking unit and the second microphone out of the output signal of the second microphone.

AUDIO PROCESSING APPARATUS, AUDIO PROCESSING METHOD, AND IMAGE CAPTURING APPARATUS

BACKGROUND OF THE INVENTION

1. Field of the Invention

The present invention relates to an audio processing apparatus, an audio processing method, and an image capturing apparatus.

2. Description of the Related Art

An audio processing apparatus is required to faithfully record audio under various environments. When shooting in the open, noise of wind (to be referred to as "wind noise" hereinafter) is especially noticeable. A lot of mechanical apparatuses and electrical processing have been proposed to suppress wind noise. For example, Japanese Patent Laid-Open No. 2006-211302 discloses a method of suppressing wind noise by pasting a wind noise suppressor (to be referred to as an "audio resistor" hereinafter) to the sound collecting portion of the body of an image capturing apparatus by an adhesive tape.

In the technique disclosed in Japanese Patent Laid-Open No. 2006-211302, however, reverberation may occur in the sound collecting portion depending on the material of the audio resistor, resulting in poorer audio quality.

SUMMARY OF THE INVENTION

The present invention has been made in consideration of the above-described problem, and provides high-quality audio by suppressing reverberation sound generated by an audio resistor while reducing wind noise using the audio resistor.

According to an aspect of the present invention, an audio processing apparatus comprises a first microphone, a second microphone, a masking unit configured to mask movement of air from outside of the apparatus to the second microphone, a high-pass filter configured to extract a frequency component within a first range of an output signal of the first microphone, a low-pass filter configured to extract a frequency component within a second range of an output signal of the second microphone, an addition unit configured to add an output signal of the high-pass filter and an output signal of the low-pass filter, and an adaptive filter provided between the second microphone and the low-pass filter and configured to estimate and learn a filter coefficient so as to minimize a difference between the output signal of the first microphone and the output signal of the second microphone, thereby suppressing a reverberation component generated in a closed space between the masking unit and the second microphone out of the output signal of the second microphone.

According to the present invention, it is possible to provide a recording apparatus that reduces wind noise by an audio resistor and suppresses reverberation sound.

Further features of the present invention will become apparent from the following description of exemplary embodiments (with reference to the attached drawings).

BRIEF DESCRIPTION OF THE DRAWINGS

The accompanying drawings, which are incorporated in and constitute a part of the specification, illustrate exemplary embodiments, features, and aspects of the invention and, together with the description, serve to explain the principles of the invention.

2

FIG. 1 is a block diagram showing the arrangement of a recording apparatus according to an embodiment;

FIGS. 2A and 2B are perspective and sectional views, respectively, showing an image capturing apparatus;

FIGS. 3A to 3F are graphs showing examples of the frequency characteristic of a microphone;

FIGS. 4A to 4D are views for explaining the attachment structure of microphones;

FIG. 5 is a block diagram showing the arrangement of a reverberation suppressor;

FIGS. 6A to 6D are timing charts showing the operation of a wind-detector according to wind noise;

FIGS. 7A to 7D are views showing the arrangements and operations of a mixer;

FIG. 8 is a block diagram showing an application example of a related art;

FIGS. 9A to 9D are graphs showing the operation sequences of a switch, variable filters, ad a variable gain;

FIG. 10 is a timing chart for explaining wind noise processing when no HPF exists;

FIG. 11 is a timing chart for explaining wind noise processing when an HPF exists;

FIGS. 12A and 12B are block diagrams showing other examples of the audio processing apparatus;

FIG. 13 is a perspective view showing an image capturing apparatus according to the second embodiment;

FIG. 14 is a block diagram showing the arrangement of an audio processing apparatus according to the second embodiment;

FIG. 15 is a block diagram showing the arrangement of an audio processing apparatus according to the third embodiment;

FIG. 16 is a block diagram showing the arrangement of an audio processing apparatus according to the fourth embodiment; and

FIGS. 17A and 17B are views for explaining the positional relationship between object sounds and microphones according to the fourth embodiment.

DESCRIPTION OF THE EMBODIMENTS

Various exemplary embodiments, features, and aspects of the invention will be described in detail below with reference to the drawings.

First Embodiment

A recording apparatus and an image capturing apparatus including the recording apparatus according to the first embodiment of the present invention will be described below with reference to FIGS. 1 to 11.

FIG. 1 is a block diagram showing the arrangement of the recording apparatus according to this embodiment. FIGS. 2A and 2B are perspective and sectional views, respectively, showing the image capturing apparatus (camera) including the recording apparatus shown in FIG. 1. Reference numeral 1 denotes an image capturing apparatus; 2, a lens attached to the image capturing apparatus 1; 3, a body of the image capturing apparatus 1; 4, an optical axis of the lens; 5, a photographing optical system; and 6, an image sensor. Reference numeral 30 denotes a release button; and 31, an operation button. A first microphone 7a and a second microphone 7b are provided in the image capturing apparatus 1. Opening portions 32a and 32b are provided in the body 3 for the microphones 7a and 7b, respectively. An audio resistor 41 is pasted to the opening portion 32b. The audio resistor 41 can also be formed by making the body 3 have an uneven thickness or using an extra part, as will be described later. The

image capturing apparatus 1 can simultaneously perform image acquisition and audio recording using the microphones 7a and 7b.

The moving image shooting operation of the image capturing apparatus 1 will be explained. When the user presses a live view button (not shown) before moving image shooting, the image on the image sensor 6 is displayed on a display device provided in the image capturing apparatus 1 in real time. In synchronism with the operation of a moving image shooting button, the image capturing apparatus 1 obtains object information from the image sensor 6 at a set frame rate and audio information from the microphones 7a and 7b simultaneously, and synchronously records these pieces of information in a memory (not shown). Shooting ends in synchronism with the operation of the moving image shooting button.

The arrangement of an audio processing apparatus (Audio-IC) 51 will be described with reference to FIG. 1. Reference numeral 52 denotes a variable high-pass filter (HPF); 53, a reverberation suppressor formed from, for example, a reverberation suppression adaptive filter; 54a and 54b, first A/D converters (ADCs) that digitize the signals output from the microphones; 55, a first delay device (DL) 55; and 56a and 56b, DC component cutting HPFs.

Reference numeral 61 denotes an automatic level controller (ALC). The ALC 61 includes variable gains 62a and 62b for level control, and a level controller 63.

A mixer 71 mixes the signal of the first microphone 7a and that of the second microphone 7b. The mixer 71 includes a low-pass filter (LPF) 72, a variable HPF 73, a variable gain 74, and an adder 75.

Reference numeral 81 denotes a wind-detector. The wind-detector 81 includes bandpass filters (BPFs) 82a and 82b, a subtracter 83, a second A/D converter (ADC) 84, a second delay device 85, and a level detector 86.

Reference numeral 87 denotes a switch that controls the reverberation suppressor 53; 88, a switch that controls the mixer 71; and 89, a mode switching operation unit.

Referring to FIGS. 1, 2A, and 2B, the opening portions 32a and 32b for the microphones are provided in the body 3. The audio resistor 41 that covers the second microphone 7b is provided on the opening portion 32b to mask movement of air from the outside of the apparatus to the second microphone 7b. On the other hand, the opening portion 32a is not provided with such an audio resistor so that the first microphone 7a can faithfully acquire an object sound. The audio resistor 41 is provided in tight contact with the body 3. Movement of air is here assumed to be air movement by wind. For example, a material such as porous PTFE that allows air to move more slowly than air moved by wind but does not allow the wind to pass through can also be used as the audio resistor.

In the audio processing apparatus 51, the signal from the first microphone 7a is processed by the HPF 52 and then undergoes analog/digital conversion (A/D conversion) of the ADC 54a. The first delay device 55 delays the output from the ADC 54a by an appropriate amount. On the other hand, in the audio processing apparatus 51, the signal from the second microphone 7b is A/D-converted by the ADC 54b and then undergoes reverberation suppression of the reverberation suppressor 53. The operation of the reverberation suppressor 53 and how to cause the first delay device 55 to apply a delay will be described later.

The outputs from the first delay device 55 and the ADC 54b are processed by the DC component cutting HPFs 56a and 56b, respectively. The HPFs 56a and 56b aim at removing the offset of the analog part and need only remove components

below the audible frequency range from the DC. To do this, the cutoff frequency of the HPFs 56a and 56b is set to, for example, about 10 Hz.

The outputs from the HPFs 56a and 56b are input to the ALC 61 and undergo gain control of the variable gains 62a and 62b. At this time, the variable gains 62a and 62b are synchronously controlled to make the two signal levels identical. The level controller 63 receives the outputs from the variable gains 62a and 62b and appropriately controls the levels so as to effectively use the dynamic range without causing saturation. At this time, the level controller 63 performs level control not to cause saturation of a larger one of the outputs from the variable gains 62a and 62b.

The outputs from the variable gains 62a and 62b are input to the mixer 71. The output from the variable gain 62a is passed through the HPF 73 and sent to the adder 75. On the other hand, the output from the variable gain 62b is sent to the adder 75 via the LPF 72 and the variable gain 74. The output mixed by the adder 75 is output as the audio after wind noise processing.

The output from the first microphone 7a and the output from the reverberation suppressor 53 are input to the BPFs 82a and 82b of the wind-detector 81, respectively. The BPFs 82a and 82b aim at passing components within the range where the object sound can faithfully be acquired by the second microphone 7b. For this reason, the passband is set to, for example, about 30 Hz to 1 kHz. However, the upper limit set value of the frequency can be changed by the structure of the audio resistor 41 or the like. Details will be described later together with the frequency characteristic of the second microphone 7b.

The output from the BPF 82a is A/D-converted by the second ADC 84 and sent to the second delay device 85. How to cause the second delay device 85 to apply a delay will be described later together with the operation of the reverberation suppressor 53.

The subtracter 83 calculates the difference between the outputs from the second delay device 85 and the output from the BPF 82b and sends the result to the level detector 86. The operation of the level detector 86 will be described later. The level detector 86 determines the strength of wind, and the switch 87 is controlled to switch feedback to the reverberation suppressor 53. The detection result of the level detector 86 is also used to control the switch 88 for controlling the mixer 71. When the user sets the mode switching operation unit 89 to OFF, the switch 88 operates to always select processing in the windless state to be described later. On the other hand, when the user sets the mode switching operation unit 89 to Auto, the switch 88 operates to change the cutoff frequencies of the HPF 52 and the HPF 73 and the variable gain 74 in accordance with the wind strength determined by the level detector 86. Details of this processing will be described later.

The effects and desired characteristics of the audio resistor 41 and wind noise reduction will be explained with reference to FIGS. 1, 3A to 3F, and 4A to 4D. FIGS. 3A to 3F are graphs schematically showing the frequency characteristic of the microphone. The abscissa represents the frequency, and the ordinate represents the gain. FIG. 3A shows the object sound acquisition characteristic of the first microphone 7a. FIG. 3B shows the object sound acquisition characteristic of the second microphone 7b. FIG. 3C shows the wind noise acquisition characteristic of the first microphone 7a. FIG. 3D shows the wind noise acquisition characteristic of the second microphone 7b. FIG. 3E shows the object sound acquisition characteristic of the output of the mixer 71. FIG. 3F shows the wind noise acquisition characteristic of the output of the mixer 71. To clarify the characteristic difference between the

first microphone 7a and the second microphone 7b, the characteristics of the first microphone 7a are indicated by the broken lines in FIGS. 3B and 3D. In FIGS. 3A and 3B, f_0 represents the structural cutoff frequency by the audio resistor 41, and f_1 represents the cutoff frequency of the LPF 72 and the HPF 73 in the mixer 71 shown in FIG. 1.

As shown in FIG. 3A, the object sound acquisition characteristic of the first microphone 7a may flat in the audible frequency range. This allows to faithfully acquire the object sound. As shown in FIG. 3B, the second microphone 7b has a different characteristic because the audio resistor 41 is provided to mask movement of air from the object. The second microphone 7b relatively faithfully passes the audio signal at a frequency lower than the cutoff frequency by the audio resistor 41. This is because the sound that is a compressional wave of air excites the audio resistor 41, and the audio resistor 41 thus excites the air in the apparatus in the same way. On the other hand, the second microphone 7b masks the audio signal at a frequency higher than the cutoff frequency by the audio resistor 41. This is because although the sound that is a compressional wave of air excites the audio resistor 41, the density is inverted before the audio resistor 41 starts vibrating, and the air cannot move. That is, the audio resistor 41 acts as a structural LPF. The frequency f_0 at which the structural cutoff begins will be referred to as the cutoff frequency of the audio resistor 41.

The power of wind noise is known to concentrate to the lower frequency range. For example, as for the power of wind noise in the first microphone 7a, a characteristic that rises from about 1 kHz to the lower frequency side is obtained in many cases, as shown in FIG. 3C. Even if the shape is different from that shown in FIG. 3C, low-frequency components (equal to or lower than 500 Hz) are dominant in the wind noise. As shown in FIG. 3D, the rise of the low-frequency components of wind noise is small in the second microphone 7b. Near the first microphone 7a, a large atmospheric pressure difference is readily generated because of a turbulent flow or the like. For the second microphone 7b, however, such a large atmospheric pressure difference is not caused by a turbulent flow or the like because the audio resistor 41 is provided to mask movement of air from the object. This is the reason why the rise of the low-frequency components of wind noise is small in the output of the second microphone 7b.

Consider processing of these signals by the mixer 71. As described above with reference to FIG. 1, the signal of the first microphone 7a is processed by the HPF 73. This corresponds to cutting a portion 91 in FIG. 3A and a portion 93 in FIG. 3C. The signal of the second microphone 7b is processed by the LPF 72. This corresponds to cutting a portion 92 in FIG. 3B and a portion 94 in FIG. 3D. When passing through the adder 75, an object sound characteristic as shown in FIG. 3E is obtained, and a wind noise characteristic as shown in FIG. 3F is obtained. The portions 91, 92, 93, and 94 are dominant at portions 91a, 92a, 93a, and 94a shown in FIGS. 3E and 3F. Note that the expression "dominant" is used because the counterpart is not necessarily zero because of the characteristics of the LPF 72 and the HPF 73. As is apparent from FIGS. 3E and 3F, the output of the mixer 71 has a flat object sound characteristic in the audible frequency range and a wind noise characteristic equal to the characteristic of the microphone provided with the audio resistor 41.

FIGS. 4A to 4D illustrate examples of the attachment structure of the microphones. Referring to FIGS. 4A to 4D, reference numerals 33a and 33b denote holding elastic bodies of the first microphone 7a and the second microphone 7b, respectively; and 34, a sleeve that holds the second microphone 7b and the audio resistor 41.

FIG. 4A shows an example in which the audio resistor 41 is pasted outside the body 3. In the example of FIG. 4A, the audio resistor 41 can be pasted after the apparatus has been assembled. This enables to improve the assembling efficiency.

FIG. 4B shows an example in which the audio resistor 41 is pasted inside the body 3. In the example of FIG. 4B, since the audio resistor 41 is not exposed to the outside the body 3, a fine outer appearance can be obtained.

FIG. 4C shows an example in which part of the body 3 also functions as the audio resistor 41. In the example of FIG. 4C, the part of the body 3 serving as the audio resistor 41 is made so thin as to be vibrated by a sound wave. In the example of FIG. 4C, since it is unnecessary to paste the audio resistor 41 to the body 3, and the number of parts can be reduced, a fine outer appearance can be obtained. In the example of FIG. 4C, however, since the body 3 and the audio resistor 41 are integrated, the degree of freedom of design generally decreases (the strength of the body 3 may be limited by the thickness of the portion that forms the audio resistor 41, resulting in difficulty in meeting the requirements simultaneously).

FIG. 4D shows an example in which the sufficiently rigid sleeve 34 holds the second microphone 7b and the audio resistor 41. The sleeve 34 preferably has a primary resonance frequency sufficiently higher than the band of the frequency to be acquired by the second microphone 7b (this means that the resonance frequency of the sleeve 34 is higher than f_0 in FIGS. 3A and 3B). In the example of FIG. 4D, the audio resistor 41 is attached to the highly rigid sleeve 34. It is therefore possible to obtain a desired audio signal in the passband (at a frequency lower than f_0 in FIGS. 3A and 3B) without being affected by the unnecessary resonance of the attachment structure.

The reverberation suppressor 53 will be described next with reference to FIGS. 1 and 5. Since the second microphone 7b is covered by the audio resistor 41, reverberation may occur in the closed space. In this embodiment, the reverberation suppressor 53 is provided to suppress such reverberation.

FIG. 5 shows the detailed arrangement of the reverberation suppressor 53. The reverberation suppressor 53 is formed from an adaptive filter. This adaptive filter estimates and learns the filter coefficient so as to minimize the output of the subtractor 83, that is, the difference between the output signal of the first microphone 7a and the output signal of the second microphone 7b, which represents the level of wind noise, as will be described below in detail. Out of the output signal of the second microphone 7b, the reverberation component generated in the closed space between the audio resistor 41 and the second microphone 7b is thus suppressed. Using such an adaptive filter makes it possible to appropriately perform processing even if the reverberation generation state changes due to the change of the user's camera grip state or the change in the temperature.

The principle of reverberation suppression will briefly be described. Let s be the object sound, g_1 be the object sound acquisition characteristic of the first microphone 7a, g_2 be the object sound acquisition characteristic of the second microphone 7b, and r be the influence of reverberation. The object sound acquisition characteristics g_1 and g_2 equal the inverse Fourier transformation results of the characteristics in the frequency space shown in FIGS. 3A to 3F. A signal x_1 of the first microphone 7a and a signal x_2 of the second microphone 7b obtained under an environment with reverberation in the second microphone 7b are given by

$$x_1 = s * g_1$$

$$x_2 = s * g_2 * r$$

where $*$ is an operator representing convolution. As described with reference to FIGS. 3A and 3B, the first microphone 7a and the second microphone 7b can acquire similar object sounds at a frequency lower than f_0 . As shown in FIG. 1, the BPFs 82a and 82b extract only components in an appropriate band. That is, the BPFs pass frequencies lower than f_0 in FIGS. 3A and 3B within the audible frequency range. The human auditory sense exhibits an extremely low sensitivity to a band of 50 Hz or less because of its characteristic. For further details, see A characteristic curve or the like. Hence, the BPFs 82a and 82b are designed to pass frequencies of, for example, 30 Hz to 1 kHz. Letting BPF be the BPFs 82a and 82b, and $x1\_BPF$ and $x2\_BPF$ be the signals that have passed through the BPFs,

$$\begin{aligned} x1\_BPF &= s * g1 * BPF \\ x2\_BPF &= s * g2 * r * BPF \\ g1 * BPF &= g2 * BPF \end{aligned} \quad (2)$$

holds. Holding $g1 \neq g2$, and $g1 * BPF \neq g2 * BPF$ is equivalent to allowing the first microphone 7a and the second microphone 7b to acquire similar object sounds at a frequency lower than f_0 . As is apparent from equations (2), identical signals are input to the subtracter 83 in FIG. 1 when the influence r of reverberation is absent. The influence of reverberation can be reduced by operating the adaptive filter using $x1\_BPF = d$ as the desired response and $x2\_BPF = u$ as the input, as can be seen from equations (2).

When the filter of the reverberation suppressor 53 is expressed as h , an adaptive filter output y is given by

$$y(n) = h * u = \sum_{i=0}^M h_n(i)u(n-i) = \sum_{i=0}^M h_i(i)x2\_BPF(n-i) \quad (3)$$

where n indicates the signal of the n th sample, M is the filter order of the reverberation suppressor 53, and the subscript of h indicates the value of a filter h of the n th sample. As the input u , $x2\_BPF$ is used.

In addition, $x1\_BPF = d$ is used as the desired response. Hence, an error signal e is expressed as

$$e(n) = d(n) - y(n) = x1\_BPF(n) - \sum_{i=0}^M h_n(i)x2\_BPF(n-i) \quad (4)$$

Various adaptive algorithms have been proposed. For example, the update equation of h by the LMS algorithm is given by

$$h_{n+1}(i) = h_n(i) + \mu e(n)u(n-i) \quad (i=0, 1, \dots, M) \quad (5)$$

where μ is the step size parameter. According to the above-described method, an appropriate initial value h is given and updated using equation (5), thereby making u closer to d . That is, the influence r is reduced, and $x1\_BPF = x2\_BPF$ almost holds. At this time, $|h * r| = 1$ holds in the passband of the BPF. However, in an environment where the wind noise is dominant, updating of equation (5) is not correctly performed. Hence, the estimation learning of the adaptive filter is stopped by the switch 87. The control sequence of the switch 87 will be described later together with the operation of the wind-detector 81.

As described above, the reverberation suppressor 53 suppresses reverberation. In the reverberation suppressor 53, the

signal delays in accordance with the order of the adaptive filter, as is apparent from FIG. 5. To compensate for this, the audio processing apparatus in FIG. 1 includes the first delay device 55 and the second delay device 85. Typically, a delay $5 \frac{1}{2} (-M/2)$ the filter order of the reverberation suppressor 53 is given (when M is an odd number, a neighboring value is usable). At this time, for example, $h(M/2) = 1$ is set, and all the other values h are initialized to 0. This allows the adaptive algorithm to run using the initial value in the no reverberation state. If an appropriate initial value for reverberation suppression is stored in the memory, the operation may be started after initializing h to that value. For example, the initial value may be set in the following way. The filter coefficient can be estimated to some extent based on the design values such as the dimensions around the microphones 7a and 7b and the material of the structure. Hence, the filter coefficient obtained from the design values may be set as the initial value. Alternatively, the filter coefficient when the recording apparatus has been powered off may be stored in the memory and set as the initial value when activating the recording apparatus next time. Otherwise, the filter coefficient may be calculated by generating predetermined reference sound in the production process of the recording apparatus and stored in the memory, and used as the initial value when activating the recording apparatus.

The operation of the ALC 61 will be described next. The ALC is provided to effectively utilize the dynamic range while suppressing saturation of the audio signal. Since the audio signal exhibits a large power variation on the time base, the level needs to be appropriately controlled. The level controller 63 provided in the ALC 61 monitors the outputs from the variable gains 62a and 62b.

The attack operation will be explained first. Upon determining that the signal of higher level has exceeded a predetermined level, the gain is reduced by a predetermined step. This operation is repeated at a predetermined period. This operation is called the attack operation. The attack operation enables to prevent saturation.

The recovery operation will be described next. If the signal of higher level does not exceed a predetermined level for a predetermined time, the gain is increased by a predetermined step. This operation is repeated at a predetermined period. This operation is called the recovery operation. The recovery operation enables to obtain sound in a silent environment.

The variable gains 62a and 62b in the ALC 61 operate synchronously. That is, when the gain of the variable gain 62a decreases by the attack operation, the gain of the variable gain 62b also decreases as much. With this operation, the level difference between the signal channels is eliminated, and the sense of incongruity decreases when the signals of the channels are mixed by the mixer 71.

The wind-detector 81 will be described next. Let $w1$ be wind noise picked up by the first microphone 7a, and $w2$ be wind noise picked up by the second microphone 7b. The BPFs 82a and 82b do not mask the wind noise because the power of wind noise concentrates to the lower frequency range, as described above with reference to FIG. 3. For this reason, $w1 - w2$ is obtained as the output of the subtracter 83. Note that the above-described influence of reverberation is assumed to be negligible. In an actual environment as well, the influence of reverberation is negligible because it is much smaller than the wind noise.

The level detector 86 performs absolute value calculation of the output of the subtracter 83 and then appropriately performs LPF processing. The cutoff frequency of the LPF is determined based on the stability and detection speed of the wind-detector, and about 0.5 Hz suffices. The LPF operates to

integrate a signal in the masking range and directly pass a signal in the passband. As a result, the same effect as that of integration operation+HPF can be obtained. For this reason, the output becomes large when the absolute value calculation maintains high level for a predetermined time (the time changes depending on the above-described cutoff frequency). That is, this is equivalent to monitoring $\Sigma|w_1-w_2|$ for an appropriate time.

FIGS. 6A to 6D show examples of the output signal of the wind-detector 81 which changes depending on the wind strength. FIGS. 6A, 6B, and 6C are views showing signals obtained by the first microphone 7a and the second microphone 7b. The abscissa represents time, and the ordinate represents the signal level. Referring to FIGS. 6A, 6B, and 6C, the signal level +1 indicates the level at which a signal in the positive direction is saturated. FIG. 6A shows the signal in the windless state, FIG. 6B shows the signal when the wind is weak, and FIG. 6C shows the signal when the wind is strong. As is apparent, as the wind strength increases, the signal level of the first microphone 7a rises, and wind noise is generated. On the other hand, the signal level of the second microphone 7b does not so largely increase as compared to that of the first microphone 7a, as can be seen. This indicates that the wind noise is reduced by the effect of the audio resistor 41.

FIG. 6D shows a result obtained by the above-described processing of the wind-detector 81. In FIG. 6D, the abscissa represents time, like FIGS. 6A, 6B, and 6C, and the ordinate represents the output of the wind-detector. Note that the passband of the BPFs 82a and 82b is 30 Hz to 1 kHz, and the cutoff frequency of the LPF in the level detector 86 is 0.5 Hz. As is apparent, the output of the wind-detector 81 remains almost zero in the windless state and increases its value as the wind becomes stronger. In FIG. 6D, the signal near 0 sec is small because rising delays due to the influence of the LPF in the level detector 86. Until wind detection, a delay as illustrated occurs in the leading edge of the signal in FIG. 6D. When the delay is made smaller, the wind-detector is readily affected by fluctuations of wind. In this embodiment, wind detection is done with a delay as shown in FIG. 6D.

The output of the wind-detector 81 is used for the switch 87 of the above-described reverberation suppressor 53 and also used to switch the HPF 52 to be described later and switch the mixing processing in the mixer 71.

The operation of the mixer 71 will be described next with reference to FIGS. 7A to 7D. Changing the variable gain 74 and the cutoff frequency of the HPF 73 based on the output of the wind-detector 81 has been described with reference to FIG. 1. A detailed changing method will be described with reference to FIGS. 7A to 7D.

FIGS. 7A and 7C show examples of the arrangement of the mixer 71. FIGS. 7B and 7D are graphs showing methods of changing the variable parts in FIGS. 7A and 7C, respectively.

The arrangement shown in FIG. 7A will be described. The mixer 71 shown in FIG. 7A has the same arrangement as that in FIG. 1. Referring to FIG. 7A, the cutoff frequency of the LPF 72 is fixed to, for example, 1 kHz. The upper graph of FIG. 7B schematically represents the gain of the variable gain 74, and the lower graph schematically represents the cutoff frequency of the HPF 73. The abscissa of FIG. 7B is common to the two graphs. Wn1, Wn2, and Wn3 are values representing the level of wind noise and indicate that the wind noise becomes stronger in this order.

As shown in FIG. 7B, when the wind noise is smaller than the predetermined value Wn1, wind processing is unnecessary. Hence, the gain of the variable gain 74 is set to 0, and the cutoff frequency of the HPF 73 is set to 50 Hz. As a result, the signal from the second microphone 7b is completely masked

via the circuit shown in FIG. 7A, and the signal in the audible frequency range (where frequencies higher than the cutoff frequency of the HPF 73, that is, 50 Hz, are the dominant components of sound) can be obtained only from the first microphone 7a. Since the signal of the second microphone 7b provided with the audio resistor 41 need not be used, the object sound is supposedly obtained faithfully.

A case will be described in which the wind noise exceeds the level Wn1 and falls within the range from Wn1 to Wn2. At this time, the value of the variable gain 74 gradually increases, and the cutoff frequency of the HPF 73 gradually rises. The above-described control is performed to gradually increase, in the low-frequency audio signal, the ratio of the signal from the second microphone 7b provided with the audio resistor 41. The wind noise largely acts on the signal from the first microphone 7a. However, the wind noise is reduced by raising the cutoff frequency of the HPF 73.

A case will be described in which the wind noise exceeds the level Wn2 and falls within the range from Wn2 to Wn3. At this time, the value of the variable gain 74 is fixed to 1, and the cutoff frequency of the HPF 73 gradually rises. Performing the above-described control allows to further reduce the wind noise, although the audio that exists from the cutoff frequency of the LPF 72 to the cutoff frequency of the HPF 73 is lost. The cutoff frequency of the HPF 73 is not raised beyond an appropriate value because if it excessively rises, the object sound degrades too much. In the example of FIG. 7B, when the level of the wind noise exceeds Wn3, the cutoff frequency of the HPF 73 is fixed to 2 kHz and does not change any more.

The arrangement shown in FIG. 7C that is another example will be described. The mixer 71 shown in FIG. 7C includes a variable LPF 76 in place of the fixed LPF 72 and the variable gain 74. The upper graph of FIG. 7D schematically represents the cutoff frequency of the variable LPF 76, and the lower graph schematically represents the cutoff frequency of the HPF 73. The abscissa of FIG. 7D is common to the two graphs. Wn1, Wn2, and Wn3 are values representing the level of wind noise and indicate that the wind noise becomes stronger in this order.

As shown in FIG. 7D, when the wind noise is smaller than the predetermined value Wn1, wind processing is unnecessary. Hence, the cutoff frequencies of the variable LPF 76 and the HPF 73 are set to 50 Hz. As a result, the signal from the second microphone 7b is almost completely masked via the circuit shown in FIG. 7C, and the signal in the audible frequency range (where frequencies higher than the cutoff frequency of the HPF 73, that is, 50 Hz, are the dominant components of sound) can be obtained only from the first microphone 7a. Since the signal of the second microphone 7b provided with the audio resistor 41 need not be used, the object sound is supposedly obtained faithfully.

A case will be described in which the wind noise exceeds the level Wn1 and falls within the range from Wn1 to Wn2. At this time, the cutoff frequencies of the variable LPF 76 and the HPF 73 gradually rise while remaining identical. The above-described control is performed to gradually use the signal from the second microphone 7b provided with the audio resistor 41 as the low-frequency audio signal. The wind noise largely acts on the signal from the first microphone 7a. However, the wind noise is reduced by raising the cutoff frequency of the HPF 73.

A case will be described in which the wind noise exceeds the level Wn2 and falls within the range from Wn2 to Wn3. At this time, the cutoff frequency of the variable LPF 76 is fixed to 1 kHz, and the cutoff frequency of the HPF 73 further rises. The above-described control is performed to further reduce the wind noise, although the audio that exists from the cutoff

11

frequency of the variable LPF 76 to the cutoff frequency of the HPF 73 is lost. The cutoff frequency of the HPF 73 is not raised beyond an appropriate value because if it excessively rises, the object sound degrades too much. In the example of FIG. 7D, when the level of the wind noise exceeds $Wn3$, the cutoff frequency of the HPF 73 is fixed to 2 kHz and does not change any more.

An example has been described above in which the HPF 73 is operated in a range wider than that of the operations of the variable gain 74 and the variable LPF 76. The HPF 73 may be operated only in the same range as that of the operations of the variable gain 74 and the variable LPF 76 by setting $Wn2=Wn3$ obviously. When the operation is limited, the object sound can faithfully be acquired, although the wind noise reduction effect becomes small. On the other hand, the level of the wind noise generated in the first microphone 7a when the wind blows largely changes depending on the attachment structure of the microphone or the like. Settings of $Wn1$, $Wn2$, and $Wn3$ are adjusted by comparing, for example, the necessity of wind noise reduction with the necessity of faithfully acquiring an object sound.

The range where the cutoff frequency of the variable LPF or LPF changes in the example of the mixer 71 shown in FIG. 7 has been described above in detail. A preferable changeable range and the filter arrangement will briefly be described.

The mixer 71 of this embodiment mixes audio signals acquired by the plurality of microphones 7a and 7b. In the processing of mixing signals of separated bands, particularly, the signals of the plurality of microphones preferably have the same phase on the respective paths in the overlapping frequency band. If the phases are shifted by the processing in the plurality of paths, the waveforms may cancel each other because they do not accurately match. To sufficiently meet this requirement, the HPF 73 and the LPF 72 are preferably formed from FIR filters of the same order. Using the FIR filters makes it possible to consistently mix the signals even when a so-called group delay properly is obtained, and processing is performed for each band. If the cutoff frequency of the FIR filter is very low (exactly speaking, if the ratio is very low when standardizing by the ratio to the sampling frequency), a filter of a very high order is necessary for obtaining sufficient filter performance. This is derived from the fact that a number of samples are required to obtain the wave of the frequency of the masking/passing target. Since the order of the filter cannot be increased infinitely, the lower limit of the cutoff frequency changeable range is determined. In the illustrated arrangement as shown in FIG. 7C, the LPF and the HPF are variable. Hence, the order of the variable LPF 76 and the HPF 73 becomes very high if the cutoff frequency is very low. For this reason, in the examples shown in FIGS. 7B and 7D, the lower limit of the frequency is set to 50 Hz not to largely affect the signal in the audible frequency range. As described above, the frequency is not limited to 50 Hz and can appropriately be set in accordance with the calculator resource. In the example shown in FIG. 7A, only the HPF is variable. Hence, only one filter of high order as described above suffices. This arrangement has an advantage over that in FIG. 7C in terms of calculation amount reduction.

On the other hand, the upper limit of the changeable range is determined by the second microphone 7b provided with the audio resistor 41. As schematically shown in FIG. 3B, the band of the object the second microphone 7b can acquire is limited to $f1$ by the influence of the audio resistor 41. Beyond this, no object sound is obtained. Hence, in the examples shown in FIGS. 7A to 7D, the cutoff frequencies of the variable LPF 76 and the HPF 73 should be set lower. In FIGS. 3A and 3B, $f1$ should obviously satisfy $f1 < f0$.

12

The effect and variable operation of the HPF 52 will be described with reference to FIGS. 1, 3A to 3F, 6A to 6D, and 8 to 11. As described above with reference to FIGS. 3A to 3F and 6A to 6D, the wind noise concentrates to the lower frequency range and affects the first microphone 7a and the second microphone 7b in much different ways. That is, even weak wind generates large wind noise in the first microphone 7a. Problems caused by this are saturation of the ADC 54a and an inappropriate operation of the ALC 61. Saturation of the ADC 54a is easily understandable, and a description thereof will be omitted. The problem of the operation of the ALC 61 at the time of wind noise generation will be explained.

If the HPF 52 does not exist, large wind noise is generated in the first microphone 7a, as shown in FIG. 6C. Even if the wind noise and the object sound are superposed, the wind noise is assumed to be dominant. In such an environment, the ALC 61 performs level control by referring to the wind noise level of the first microphone 7a. When the HPF 73 in the mixer 71 then processes the wind noise, the level of the audio signal greatly lowers. As a result, the output of the adder 75 is very small. That is, the signal level is inappropriate.

To solve the above-described problems such as the saturation of the ADC and the inappropriate signal level, for example, the technique of patent literature 1 may be applied. FIG. 8 shows an example of the audio processing apparatus 51 of this case. The same reference numerals as in FIG. 1 denote parts having the same functions in FIG. 8. Referring to FIG. 8, the variable gains 62a and 62b are provided before the ADCs 54a and 54b to avoid their saturation. In addition, another ALC 61b is provided after wind noise processing of the mixer 71, in which a variable gain 62c and a level controller 63b prevent the signal level after wind processing from becoming inappropriate.

However, the circuit shown in FIG. 8 also has two problems. One is the increase in the circuit scale caused by performing the level control operation at two portions. The other is the increase in the quantization error caused by making the ALC 61b arranged after the mixer 71 raise the gain. That is, a level controller 63a performs level control using a signal including wind noise, and the level controller 63b performs level control using a signal including no wind noise. If the wind noise reduction effect is large, the level controller 63b needs to largely raise the gain. At this time, since the signal has already been digitized, the quantization error increases upon level control.

The quantization error will briefly be described. For example, when the gain is to be raised by 12 dB in the level controller 63b, calculation is performed to shift the digital signal to the left by 2 bits. At this time, since there is no information corresponding to lower 2 bits, the bits need to be filled with an appropriate value (for example, 0). In this case, since the lower 2 bits are always 0, only 4 can be expressed next to 0 in decimal number. Since the signals can only discretely be expressed, a quantization error occurs for natural signals (continuous).

Consider the HPF 52 shown in FIG. 1. The main components of the wind noise can be removed by appropriately setting the cutoff frequency of the HPF 52. This allows to prevent saturation of the ADC 54a and cause the ALC 61 to perform appropriate gain control (since the object sound is not buried in the wind noise at the point of ALC 61, the ALC operation according to the level of the object sound can be performed).

An example of the cutoff frequency control sequence of the HPF 52 will be described with reference to FIGS. 9A to 9D. FIG. 9A shows the operation sequence of the switch 87. FIG.

9B shows the operation sequence of the HPF 52. FIG. 9C shows the operation sequence of the variable gain 74. FIG. 9D shows the operation sequence of the HPF 73. The abscissa representing the level of wind noise is common to FIGS. 9A to 9D. Wn1, Wn2, and Wn3 are values representing the level of wind noise and indicate that the wind noise becomes stronger in this order. The operation in FIGS. 9C and 9D is the same as that in FIG. 7B, and a description thereof will not be repeated.

When the wind noise is smaller than the predetermined value Wn1, wind processing is unnecessary. Hence, the switch 87 is turned on, and the adaptive operation of the reverberation suppressor 53 described above is performed. The cutoff frequency of the HPF 52 is set to 0 Hz (=through without the HPF operation). Since the signal of the second microphone 7b provided with the audio resistor 41 need not be used, the object sound is supposedly obtained faithfully.

When the wind noise exceeds the level Wn1, wind noise is generated. Hence, the switch 87 is turned off, and the adaptive operation of the reverberation suppressor 53 described above is stopped. This control allows to suppress the inappropriate adaptive operation.

A case will be described in which the wind noise falls within the range from Wn1 to Wn2. At this time, the cutoff frequency of the HPF 52 rises stepwise within the range not to exceed the cutoff frequency of the HPF 73. Performing the above-described control enables to reduce the wind noise generated in the first microphone 7a. When the control is performed not to exceed the cutoff frequency of the HPF 73, the cutoff frequency of the HPF 52 does not largely affect the output of the HPF 73.

Effects obtained by this arrangement will be described. The HPF 52 is provided in the analog part (before the ADC) of the audio processing apparatus 51 and therefore formed from an IIR filter (an HPF formed from an RC circuit) in general. At this time, the HPF 52 cannot satisfy the group delay property. On the other hand, the phase delay is small in the passband even in the IIR filter. For this reason, even if the group delay property is not satisfied, the phase delay does not affect. Controlling the cutoff frequencies of the HPFs 52 and 73 as described above makes it possible to reduce the influence of the phase delay caused by the IIR filter. As described above, in the processing of mixing signals of separated bands, particularly, the signals of the plurality of microphones preferably have the same phase on the respective paths in the overlapping frequency band. However, even if this condition is not satisfied, the influence can be reduced. In addition, the HPF 52 is provided in the analog part of the audio processing apparatus 51. However, if the HPF 52 is configured to continuously change the cutoff frequency in the analog circuit, the circuit scale becomes large. When a circuit suitable for the control sequence described with reference to FIGS. 9A to 9D is formed, the HPF can be implemented by a simple arrangement.

FIGS. 10 and 11 show examples of signals processed by the above-described circuit. FIG. 10 shows a case in which the HPF 52 is not provided. FIG. 11 shows a case in which the HPF 52 is provided. The signals in FIG. 10 are processed in a state in which the HPF 52 is removed from the arrangement in FIG. 1. As illustrated, the graphs represent the output of the gain 62a, the output of the gain 62b, the output of the HPF 73, the output of the LPF 72, and the output of the adder 75, respectively, sequentially from the upper side. The abscissa represents time and is common to all graphs. The examples shown in FIGS. 10 and 11 indicate that the object speaks from near 2.5 sec (human voice is the sound to be collected). The

signals shown in FIGS. 10 and 11 are processed assuming that the wind noise level is Wn2 in FIGS. 9A to 9D.

Only wind noise exists before 2.5 sec, as in the graphs of FIGS. 6A to 6D. Placing focus only on this portion, the output of the gain 62a appears to be larger in FIG. 11 than in FIG. 10. This is because the gain is actually increased by the ALC 61. This is apparent from the portion after 2.5 sec where the output is superposed on the object sound.

Placing focus on the output of the gain 62b after 2.5 sec reveals that the signal in FIG. 10 obviously has a signal level lower than that of the signal in FIG. 11. This is because the gain becomes smaller because of the level control performed by the ALC 61 for the wind noise generated in the first microphone 7a, and the object sound is consequently acquired very small. On the other hand, in the signal shown in FIG. 11, the wind noise generated in the first microphone 7a is reduced by the effect of the HPF 52, and the gain of the ALC 61 is kept high as compared to the state of FIG. 10.

Placing focus on the output of the HPF 73 in FIG. 10 reveals that the wind noise is considerably reduced by appropriately processing the cutoff frequency of the HPF 73. However, since the signal level of the output of the HPF 73 is much lower than that of the output of the gain 62a, the signal level of the final output from the adder 75 is very low, as can be seen.

On the other hand, even in FIG. 11, the wind noise is considerably reduced by appropriately processing the cutoff frequency of the HPF 73, as is apparent. In addition, since the output of the LPF 72 remains large, the signal level of the final output from the adder 75 is also kept at a sufficient level, as can be seen.

As described above, when the HPF 52 is arranged on a side closer to the microphone than the ADC and the ALC, high-quality audio can be obtained.

FIGS. 12A and 12B illustrate other examples of the circuit arrangement of this embodiment. FIG. 12A shows an example in which the ALC is arranged in the analog part. FIG. 12B shows an example in which the ALC 61 is arranged after the mixer 71. Even such an arrangement enables to obtain the effects described in this embodiment.

As described above, according to the present invention, it is possible to obtain high-quality audio with suppressed reverberation while reducing wind noise by the audio resistor.

Second Embodiment

A recording apparatus and an image capturing apparatus including the recording apparatus according to the second embodiment of the present invention will be described below with reference to FIGS. 13 and 14. The same reference numerals as in the first embodiment denote parts that perform the same operations in the second embodiment.

FIG. 13 is a perspective view showing the image capturing apparatus. Although the apparatus in FIG. 13 is similar to that of FIG. 2A, an opening portion 32c for a microphone is added. A microphone 7c (not shown) is provided behind the opening portion 32c.

FIG. 14 is a block diagram for explaining the main part of an audio processing apparatus 51 corresponding to the apparatus shown in FIG. 13. In FIG. 14, the arrangement is extended to a stereo system based on the circuit including the ALC in the analog part according to the first embodiment shown in FIG. 12A. The illustrations of a reverberation suppressor 53 and a level detector 86 are simplified/changed. A first microphone 7a is extended to two microphones, unlike the first embodiment. The microphones 7a and 7c respectively constitute the left and right channels of the stereo system and are designed to have the same characteristic. On the

other hand, a second microphone **7b** is provided with an audio resistor **41** and has the same characteristic as in the first embodiment.

An HPF **52b**, a gain **62c**, an ADC **54c**, a DC component cutting HPF **56c**, and an HPF **73b** extended in FIG. 14 perform the same operations as those of the HPF **52**, the gain **62a**, the ADC **54a**, the DC component cutting HPF **56a**, and the HPF **73** described in the first embodiment, respectively. Delay devices **55a** and **55b**, a newly provided phase comparator **57**, an adder **58**, and a gain **59** whose operations change will be described here.

In the stereo recording apparatus, the signals are given the stereo effect by the phase difference between the audio signals. In the arrangement shown in FIG. 13, the second microphone **7b** is arranged between the first microphones **7a** and **7c**. In this arrangement, when the phase difference between the microphones **7a** and **7c** is considered, the phase of the signal of the second microphone **7b** exists between them. For example, when the second microphone **7b** is arranged just at the intermediate point equidistant from the microphones **7a** and **7c**, the phase also exists at the intermediate point. In the circuit shown in FIG. 14, the phase difference between the microphones **7a** and **7c** is calculated, and a delay corresponding to it is given by the delay devices **55a** and **55b**.

For example, examine a case in which the signal of the microphone **7c** delays from that of the microphone **7a**. At this time, the reverberation suppressor is controlled to comply with the intermediate signal, as will be described later. When mixing with the signal of the microphone **7a**, the phase is advanced. When mixing with the signal of the microphone **7c**, the phase is delayed. In the first embodiment, a delay $\frac{1}{2}$ ($=M/2$) the filter order of the reverberation suppressor **53** is given. The delay device **55a** gives a smaller delay, and the delay device **55b** gives a larger delay. The absolute value changes depending on the position of the microphone. For example, when the second microphone **7b** is located at the intermediate point between the first microphones **7a** and **7c**, as described above, each phase is shifted by $\frac{1}{2}$ the phase difference calculated by the phase comparator **57**. Performing the above-described processing allows to obtain an audio signal without reducing the stereo effect.

The adder **58** and the gain **59** will be explained. The adder **58** adds the signals of the microphones **7a** and **7c**. The gain **59** halves the output of the adder **58**. As a result, the output of the gain **59** is the average of the microphones **7a** and **7c**. A thus obtained audio signal has the intermediate phase between the signals of the microphones **7a** and **7c**. On the other hand, a BPF **82a** passes only a band of about 30 Hz to 1 kHz, as described above in the first embodiment. The audio processing apparatus **51** is configured to acquire even an audio signal of a frequency higher than the passband of the BPF. As for the audio signal acquirable at this time, the microphones **7a** and **7c** are arranged such that no phase inversion occurs between their signals. When observing only in the passband of the BPF **82a**, the phase difference between the signals of the microphones **7a** and **7c** is small. Hence, the levels of the signals in the passband of the BPF **82a** can be considered to be almost added. For this reason, when the gain **59** halves the output, a signal having a signal level almost equal to that of the first microphones **7a** and **7c** and a phase at the intermediate point can be obtained. In this embodiment, the reverberation suppressor **53** is operated so as to comply with the output of the gain **59** described above.

With the above-described arrangement, the present invention is easily applicable even to a stereo recording apparatus without reducing the stereo effect.

In this embodiment, a stereo apparatus (including two first microphones for acquiring a high-frequency range) has been described. The arrangement can easily be extended to a recording apparatus including more microphones.

5 Third Embodiment

A recording apparatus and an image capturing apparatus including the recording apparatus according to the third embodiment of the present invention will be described below with reference to FIG. 15. The same reference numerals as in the first embodiment denote parts that perform the same operations in the third embodiment.

The perspective view of the image capturing apparatus including the recording apparatus according to the third embodiment is omitted because it is the same as FIG. 2 of the first embodiment. FIG. 15 is a block diagram for explaining the main part of an audio processing apparatus **51** according to the third embodiment. Referring to FIG. 15, an up-sampler **96** that changes the sampling frequency of an audio signal is arranged at the preceding stage of an LPF **72**. Unlike the first embodiment, different values are set as the sampling frequencies of ADCs **54a** and **54b**. The sampling frequency of the ADC **54b** is set to be lower than that of the ADC **54a**. The sampling frequency of an ADC **84** is set to equal that of the ADC **54b**.

15 The ADC **54b**, the ADC **84**, a reverberation suppressor **53**, and the newly provided up-sampler **96** will be described.

The output from a first microphone **7a** is branched and sent to a wind-detector **81**. After passing through a BPF **82a**, the 20 output is A/D converted by the ADC **84** to a sampling frequency lower than that of the ADC **54a**. The sampling frequency is set to a value within the range that can reproduce the passband of the BPF **82a** and is preferably set to a fraction of an integer of the sampling frequency of the ADC **54a**. For 25 example, when the passband of the BPF **82a** is 30 Hz to 1 kHz, and the sampling frequency of the ADC **54a** is 48 kHz, the sampling frequency of the ADC **84** is set to 3 kHz, that is, $\frac{1}{16}$ of 48 kHz. The output of the ADC **84** is delayed by a delay device **85** and sent to a subtracter **83**.

30 On the other hand, the signal from a second microphone **7b** is A/D-converted by the ADC **54b** to a sampling frequency that is the same as that of the ADC **84**. After the reverberation suppressor **53** has suppressed the reverberation, the signal is 35 branched and sent to the wind-detector **81**. After passing through a BPF **82b**, the signal is sent to the subtracter **83**. The sampling frequency is suppressed to $\frac{1}{16}$ by the ADC **54b**. For 40 this reason, even if a filter order M of the reverberation suppressor **53** is $\frac{1}{16}$ the conventional filter order, the same effect as in the conventional reverberation suppressor can be 45 obtained, leading to a decrease in the circuit scale and the calculation amount. As the filter order M of the reverberation suppressor **53** decreases, the delay amount of a delay device **85** also decreases. The operations of the subtracter **83** and the 50 remaining parts are the same as those in the first embodiment, and a description thereof will be omitted.

55 One of the branched outputs of the reverberation suppressor **53** passes through an HPF **56b**, undergoes gain control of an ALC **61**, and is sent to the up-sampler **96**. The up-sampler **96** converts the output of a variable gain **62b** to the same 60 sampling frequency as that of the ADC **54a** and sends it to an LPF **72**. Although up-sampling may cause aliasing, the LPF **72** reduces high-frequency components and removes the aliasing.

65 The operations of an HPF **52** at the succeeding stage of the first microphone **7a**, the LPF **72**, and the remaining parts are the same as those in the first embodiment, and a description thereof will be omitted.

With the above-described arrangement, the low-frequency components are down-sampled, and reverberation suppression processing is performed, the circuit scale and the calculation amount can be decreased. In addition, performing up-sampling after the reverberation suppression processing allows to obtain a high-quality audio.

Fourth Embodiment

A recording apparatus and an image capturing apparatus including the recording apparatus according to the fourth embodiment of the present invention will be described below with reference to FIGS. 16, 17A, and 17B. The same reference numerals as in the first embodiment denote parts that perform the same operations in the fourth embodiment.

The perspective view of the image capturing apparatus including the recording apparatus according to the fourth embodiment is omitted because it is the same as FIG. 2 of the first embodiment. FIG. 16 is a block diagram for explaining the main part of an audio processing apparatus 51 according to the fourth embodiment. Referring to FIG. 16, a cross-correlation calculator 97 receives the branched outputs of a BPF 82b and a delay device 85, calculates the cross-correlation value of the two signals, and determines whether there are a plurality of audio source arrival directions. The operation of the cross-correlation calculator 97 will be described later. FIGS. 17A and 17B schematically show the positional relationship between the audio sources of object sounds and microphones 7a and 7b and audio propagation. FIG. 17A is a schematic view showing a case in which an object sound propagates from one direction. FIG. 17B is a schematic view showing a case in which object sounds propagate from two directions.

A problem posed when object sounds propagate from two directions will be described with reference to FIGS. 17A and 17B. Let s_1 be an object sound generated by an object O1, and s_2 be an object sound generated from a direction different from that of the object O1. Let $T1a$ be the transfer function of an audio signal that propagates from the object O1 to the microphone 7a, and $T1b$ be the transfer function of an audio that propagates to the microphone 7b. Similarly, let $T2a$ and $T2b$ be the transfer functions of audio signals that propagate from the object O2 to the microphones 7a and 7b, respectively. When the audio source of the object sound exists in one direction, as shown in FIG. 17A, audio signals x_1 and x_2 acquired by the microphones 7a and 7b are given by

$$x_1 = s_1 * T1a$$

$$x_2 = s_1 * T1b \quad (6)$$

A delay occurs between the signal x_1 of the microphone 7a and the signal x_2 of the microphone 7b because of the difference between the distances of the microphones 7a and 7b from the object sound. However, this only causes a temporal shift, and the correlation between the two signal is very high. On the other hand, when the object sounds propagate from two directions, as shown in FIG. 17B, the audio signals x_1 and x_2 acquired by the microphones 7a and 7b are given by

$$x_1 = s_1 * T1a + s_2 * T2a$$

$$x_2 = s_1 * T1b + s_2 * T2b \quad (7)$$

Delays occur between the signal x_1 of the microphone 7a and the signal x_2 of the microphone 7b because of the differences between the distances of the microphones 7a and 7b from the two objects O1 and O2. As the distance between the two objects O1 and O2 increases, the delay amounts by $T1a$ and $T1b$, and $T2a$ and $T2b$ obtain shifts, and the correlation

between the two signal lowers. As a result, a reverberation suppressor 53 is not correctly updated.

In the image capturing apparatus including the recording apparatus according to the fourth embodiment, the cross-correlation calculator 97 is provided. Learning of the reverberation suppressor is stopped when the cross-correlation value between the two signals is smaller than a predetermined value, thereby solving the above-described problem.

The operation of the cross-correlation calculator 97 will be described. Branched outputs from the BPF 82b and the delay device 85 are sent to the cross-correlation calculator 97. These are audio signals of the microphones 7a and 7b, which have passed through the BPFs 82a and 82b in a frequency band of 30 Hz to 1 kHz. These signals are represented by $x1_BPF$ and $x2_BPF$. The cross-correlation calculator 97 calculates the cross-correlation value between the two signals in the following way. A cross-correlation value $R(n)$ between the two signals of the nth sample when the data length is N is given by

$$R(n) = \frac{1}{N} \sum_{m=0}^{N-1} x1_BPF(m) \cdot x2_BPF(m+n) \quad (8)$$

When this is normalized by $x1_BPF$, we obtain

$$R_{norm}(n) = \frac{R(n)}{\frac{1}{N} \sqrt{\sum_{m=0}^{N-1} (x1_BPF(m))^2}} \quad (9)$$

If the object sound propagates from one direction, $R_{norm}(n)$ ideally has 1 as the maximum value. However, if there are two or more audio sources of object sounds, the cross-correlation between the two signals is low, and $R_{norm}(n)$ is smaller than 1. When the normalized cross-correlation value $R_{norm}(n)$ is smaller than a predetermined value $Rn1$, it is determined that the number of audio sources of object sounds is two or more. Hence, a switch 87 is turned off to stop the adaptive operation of the reverberation suppressor 53.

In the image capturing apparatus according to the fourth embodiment as well, the switch 87 is turned on/off based on the detection result of the level detector 86, as in the first embodiment. That is, when the cross-correlation calculator 97 detects that the cross-correlation value is smaller than $Rn1$, or the level detector 86 detects that the wind noise level exceeds $Wn1$, the switch 87 is turned off to stop the adaptive operation of the adaptive filter of the reverberation suppressor 53.

This control makes it possible to perform an appropriate adaptive operation even when object sounds propagate from two or more directions and thus obtain a high-quality audio.

Other Embodiment

Apparently, the present invention can be accomplished by supplying an apparatus with a storage medium in which a software program code which implements the functions of the above exemplary embodiments is stored. In this case, a computer (or central processing unit (CPU) or micro-processor unit (MPU)) including a control unit of the apparatus supplied with the storage medium reads out and executes the program code stored in the storage medium.

In this case, the program code itself read from the storage medium implements the functions of the above exemplary

embodiments. Thus, the program code itself and the storage medium in which the program code is stored constitute the present invention.

For example, a flexible disk, a hard disk, an optical disk, a magneto-optical disk, a compact disc read-only memory (CD-ROM), a compact disc recordable (CD-R), a magnetic tape, a nonvolatile memory card, and a ROM can be used as the storage medium for supplying the program code.

In addition, apparently, the above case includes a case where a basic system or an operating system (OS) or the like which operates on the computer performs a part or all of processing based on instructions of the above program code and where the functions of the above exemplary embodiments are implemented by the processing.

Besides, the above case also includes a case where the program code read out from the storage medium is written to a memory provided on an expansion board inserted into a computer or to an expansion unit connected to the computer, so that the functions of the above exemplary embodiments are implemented. In this case, based on instructions of the program code, a CPU or the like provided in the expansion board or the expansion unit performs a part or all of actual processing.

Aspects of the present invention can also be realized by a computer of a system or apparatus (or devices such as a CPU or MPU) that reads out and executes a program recorded on a memory device to perform the functions of the above-described embodiments, and by a method, the steps of which are performed by a computer of a system or apparatus by, for example, reading out and executing a program recorded on a memory device to perform the functions of the above-described embodiments. For this purpose, the program is provided to the computer for example via a network or from a recording medium of various types serving as the memory device (for example, computer-readable medium). In such a case, the system or apparatus, and the recording medium where the program is stored, are included as being within the scope of the present invention.

While the present invention has been described with reference to exemplary embodiments, it is to be understood that the invention is not limited to the disclosed exemplary embodiments. The scope of the following claims is to be accorded the broadest interpretation so as to encompass all modifications, equivalent structures, and functions.

This application claims the benefit of Japanese Patent Application No. 2010-277419, filed Dec. 13, 2010, which is hereby incorporated by reference herein in its entirety.

What is claimed is:

1. An audio processing apparatus comprising:
a first microphone;
a second microphone;
a masking unit configured to mask movement of air from outside of the apparatus to said second microphone so that a frequency higher than a first frequency of an output signal of the second microphone is attenuated, wherein the first frequency is higher than a frequency corresponding to a wind noise;
a high-pass filter configured to extract a frequency component within a first range, which is higher than the first frequency, of an output signal of said first microphone; an adaptive filter configured to process the output signal of the second microphone in which the frequency higher than the first frequency of an output signal of the second microphone is attenuated, wherein the adaptive filter processes the output signal of the second microphone so that a difference between the

output signal of the first microphone and the output signal of the second microphone is minimized; a low-pass filter configured to extract a frequency component within a second range, which is lower than the first frequency, of an output signal of said second microphone;

an addition unit configured to add an output signal of said high-pass filter and an output signal of said low-pass filter.

2. The apparatus according to claim 1, further comprising a delay unit configured to delay the output signal of said first microphone,

wherein a delay amount of said delay unit is determined in accordance with an order of said adaptive filter.

3. The apparatus according to claim 1, wherein said adaptive filter stops an adaptive operation when a difference between the output signal of said first microphone and the output signal of said second microphone exceeds a predetermined value.

4. The apparatus according to claim 1, further comprising: a first A/D converter configured to digitize the output signal of said first microphone;

a second A/D converter configured to digitize the output signal of said second microphone, at a preceding stage of said adaptive filter, to a sampling frequency lower than a sampling frequency of said first A/D converter; and an up-sampler configured to change the sampling frequency of the output signal of said second microphone, which has been digitized by said second A/D converter and has passed through said adaptive filter, to the same sampling frequency as the sampling frequency of said first A/D converter.

5. The apparatus according to claim 1, further comprising a cross-correlation calculation unit configured to calculate a cross-correlation value between the output signal of said first microphone and the output signal of said second microphone and determine based on the calculated cross-correlation value whether a plurality of arrival directions of audio sources exist, wherein if said cross-correlation calculator determines that the plurality of arrival directions of audio sources exist, said adaptive filter is controlled to stop an adaptive operation.

6. The apparatus according to claim 1, wherein an initial value of the filter coefficient of said adaptive filter is set based on design values of structures of said first microphone and said second microphone.

7. The apparatus according to claim 1, wherein said adaptive filter stores, in a memory, the filter coefficient of said adaptive filter when the audio processing apparatus has been powered off, and sets, as an initial value, the filter coefficient stored in the memory when activating the apparatus next time.

8. The apparatus according to claim 1, wherein an initial value of the filter coefficient of said adaptive filter is set based on the filter coefficient of said adaptive filter when a predetermined reference sound is input to said first microphone and said second microphone.

9. An audio processing method of an audio processing apparatus including a first microphone, a second microphone, and a masking unit configured to mask movement of air from outside of the apparatus to the second microphone so that a frequency higher than a first frequency of an output signal of the second microphone is attenuated, wherein the first frequency is higher than a frequency corresponding to a wind noise, the method comprising:

a first extraction step of extracting a frequency component within a first range, which is higher than the first frequency, of an output signal of the first microphone;

21

an adaptive filtering step of processing the output signal of the second microphone in which the frequency higher than the first frequency of an output signal of the second microphone is attenuated, wherein the output signal of the second microphone is processed so that a difference between the output signal of the first microphone and the output signal of the second microphone is minimized; a second extraction step of extracting a frequency component within a second range, which is lower than the first frequency, of an output signal of the second microphone; an addition step of adding a signal extracted in the first extraction step and a signal extracted in the second extraction step.

10. The apparatus according to claim 1, further comprising:

a first filter configured to extract a frequency component lower than the first frequency from the output signal of the first microphone;
a second filter configured to extract a frequency component lower than the first frequency from an output signal of the adaptive filter,
wherein the adaptive filter processes the output signal of the second microphone so that a difference between an output of the first filter and an output of the second filter is minimized.
